FASTENER CLIP

Filed Oct. 10, 1928

UNITED STATES PATENT OFFICE

HENRY S. DE FOREST, OF EAST ORANGE, NEW JERSEY, AND LUDOLF HERES DE WYK,
OF DERBY, CONNECTICUT

FASTENER CLIP

Application filed October 10, 1928. Serial No. 311,480.

Our invention relates to new and useful improvements in a fastener clip for pail covers and the like and has for one of its objects to provide a simple and effective device of this character whereby a cover may be readily and quickly fastened to a pail, tub or the like.

Another object of the invention is to provide a fastener clip, one portion of which is designed to engage a hoop on a pail, tub or the like and another portion disposed across the cover, and if found desirable, attached thereto whereby said cover will be securely held in place.

A further object of the invention is to provide a fastener clip which may be first attached to the cover of a pail, tub or the like and when said cover is placed in position, a part of the clip will be located for connection with a hoop of the pail, tub or the like and by certain manipulations brought into positive engagement with the hoop and such position fixed by a holding tab which may be readily released when occasion requires the removal of the cover.

A still further object of the invention is to form a fastener clip from suitable pliable material to produce a strap, a hanger connected with one end of the strap by means of a lip, said hanger including a holding tab passing between parts of the lip and adapted to be bent down over the strap to lock a hook on the outer end of the hanger against a hoop on the pail, tub or the like.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this invention, in which:

Fig. 1, is a fragmentary sectional view of a pail, tub or other receptacle showing the formation of the hoops with which our improved fastener clip is to be used.

Fig. 2, is an enlarged fragmentary sectional view showing the fastener clip secured to the cover and ready to be fastened in place.

Fig. 3, is a similar view illustrating the final position of the clip for fastening the cover on the receptacle and also showing in dotted lines the intermediate position of the clip.

Fig. 4, is a top or plan view of a similar fastener clip showing the use of prongs at the inner end of the strap for connecting the latter to the cover.

Fig. 5, is an edge view thereof showing it attached to the cover.

Fig. 6, is an end elevation without the cover.

Fig. 7, is a fragmentary plan view of a cover with portions broken away and illustrating a form of clip wherein a hanger is produced at both ends of the strap.

Fig. 8, is a plan view of a modified form of the clip which may be produced from wire.

Fig. 9, is an end elevation thereof.

Fig. 10, is a side elevation showing it attached to a section of the cover.

Fig. 11, is a plan view of a further modified form of the invention.

Fig. 12, is an edge view thereof showing it attached to a section of a cover.

In carrying out the invention as herein embodied, 15 represents a receptacle of any suitable material and any desirable construction, particularly such as are used in candy pails or tubs and the parts are held together or straightened by hoops 16, 17 and 18. The hoop 16 is provided with a roll, flange, bead or the like 19, preferably along its lower edge so that the upper portion may be fashioned to cover the upper edge of the receptacle on which the cover 20 rests and a part of the inside face of the receptacle. Of course it is to be understood that any other substitute anchoring element may be provided.

The fastener clip illustrated in Figs. 2 to 6 inclusive comprises a flat strip of suitable material, preferably metal, having a portion partially cut out intermediate its ends to provide a holding tab 21 which passes through the opening, thus provided when the strip 23 is bent or fashioned to produce a strap 23 which overlies the receptacle cover 20.

The strap 23 may be fastened to said cover in any suitable manner as by a staple 24 passing through the strap and cover and

clinched at the inner end or by prongs 25 fashioned from the inner end of the strap and projected through the cover where the ends may be clinched, as shown in Fig. 5.

At the outer end of the strap, a portion is bent inward at a suitable angle to the strap to provide a lip 26 and from this depends the hanger 27 having a hook 28 or other similar formation at its lower end for engagement with the anchoring element 19 of the hoop 16.

When the cover is placed in position on the receptacle, as shown in Fig. 2, the hook 28 lies directly under the anchoring element 19 and by drawing the lip 26 up against the projecting end of the strap 23, as shown in Fig. 3, the hook 28 will be brought into snug engagement with the anchoring element 19, and the holding tab 21 moved upward as indicated in dotted lines and thereafter said holding tab may be bent down against the strap, as shown in full lines in Fig. 3 thereby firmly fastening the cover in place.

When necessary to remove the cover, it is a relatively easy matter to bend the tab upward and then force the hanger downward to disengage the hook 28 from the receptacle hoop. The fastener clip being of fairly stiff but pliable material, when the parts are fastened in position, the clip will not be accidentally displaced but when necessary, it may be easily removed.

In Fig. 7, we have shown a similar construction so far as the hanger, lip and holding tab are concerned but the strap is of such length as to pass entirely across the receptacle cover and therefore need not be fastened to the cover in which case there are hangers, lips and tabs at both ends of a strap 29, and if found desirable, two of these straps may be fastened together by a rivet 30 at their point of crossing.

With such a construction the clip may be placed upon the cover after the latter has been properly positioned and the hooks then caused to project beneath the anchoring elements and the parts afterward fastened in place in the same manner as above described.

In Figs. 8 to 10 inclusive, we have shown a clip embodying the same feature but constructed of wire or some strand material in which case the strand is bent intermediate its ends as at 31 and then carried along in parallelism to form the holding tab 32 and the lower portions of these two parallel strands are bent upward to form the hooks 33 and then outward and of the same contour as the hooks wherefrom the strands are carried upward parallel with the tab strands as at 34 to produce the hanger, but these are then bent backward to form lips 35 and from said lips the strands project firmly, preferably with their major portions diverging to produce the strap elements 36 and the terminals of such strap elements are bent downward so as to form prongs 37

which may be projected through the cover and clinched as shown in Fig. 10.

This form of the device is used identically the same as that illustrated in Figs. 2 and 3.

The modification illustrated in Figs. 11 and 12 is formed from spring metal and includes a strap 38 which may be fastened to the receptacle cover by a staple 39 or its equivalent, a spring bow portion 40 from which depends the hanger 41 having its terminal fashioned in the form of a hook 42 for engagement with the anchoring element 19 carried by the receptacle.

In this form of the invention the hook 42 is forced under the anchoring element against the action of the spring bow and after being released, said spring bow will draw the hook snugly up against the anchoring element and hold the cover firmly on top of the receptacle. Such a construction causes the cover to be firmly held in place under spring tension and by the necessary pressure upon the spring bow portion 40 the hook may be readily disengaged from the anchoring element.

Of course we do not wish to be limited to the exact details of construction as herein shown, as these may be varied within the limits of the appended claims without departing from the spirit of our invention.

Having thus fully described our invention, what we claim as new and useful is:

1. As an article of manufacture, a fastener clip for the covers of receptacles including a strap to overlie the receptacle cover, a tab formed by partially cutting a section from the clip intermediate its ends, a lip produced by bending a portion of the clip material toward the free end of the strap, thus causing the tab to project through the aperture formed by the production of said tab, a hanger depending from the lip and a hook at the lower end of said hanger for engagement with an anchoring element on a receptacle.

2. A fastener clip for the cover of a receptacle constructed from a single piece of material having a portion partially cut therefrom to provide a holding tab and an aperture, said piece of material being fashioned to provide a strap to overlie the cover, a lip turned back upon the strap, a hanger depending from the lip, the aforementioned tab projecting from the upper end of said hanger through the aperture and adapted to be bent over on to the strap after the lip has been forced against the opposite face of said strap which projects beyond the edge of the cover, means to fasten the strap to the cover, and a hook formed from the lower end of the hanger and brought into engagement with an anchoring element on the receptacle during the closing of the lip against the strap.

3. A device of the kind described comprising

ing a hanger having a hook at its lower end for engagement with an anchoring means carried by a receptacle below its upper edge, a lip projecting outwardly from the face of the hanger opposite the hook and at the other end of said hanger, a strap projecting from the lip for securement to the receptacle cover, said lip to be drawn against the under-side of the contiguous end of the strap to move the hook into positive engagement with the anchoring means, and means carried by the upper end of the hanger and passing between portions of the strap for disposition over said strap after the lip has been drawn against the under side thereof.

4. A fastener clip for use in connection with a receptacle having a hoop provided with an outstanding anchoring element, and a cover which rests upon the upper edge of the receptacle, comprising means for securement to the outer face of the cover with a portion projecting beyond the edge thereof, means for engagement with the anchoring element of the hoop, a lip connecting both of said means and the closing of which draws the second named means into engagement with the anchoring element, and a tab carried by the second mentioned means bendable into a position overlying the first mentioned means to hold the parts in place.

In testimony whereof, we have hereunto affixed our signatures.

HENRY S. DE FOREST.
LUDOLF HERES DE WYK.
